[57] CLAIM

The ornamental design for a fire-resistant safe, as shown and described.

DESCRIPTION

FIG. 1 is a typical side elevational view of a fire-resistant safe showing my new design;

FIG. 2 is a top plan view;

FIG. 3 is a bottom plan view; and,

FIG. 4 is a cross-section of elevational view to explain inner structure of the present design.

FIG. 1

FIG. 2

FIG. 3

FIG. 4
